W. R. SMITH

METAL STRAIGHTENING APPARATUS

Filed May 29, 1924

UNITED STATES PATENT OFFICE.

WILLIAM R. SMITH, OF TOPEKA, KANSAS.

METAL-Straightening APPARATUS.

Application filed May 29, 1924. Serial No. 716,730.

- This invention relates to certain improvements in metal straightening apparatus and has relation more particularly to a device of this general character of a roll type and it
- 5 is an object of the invention to provide a novel and improved apparatus of this kind especially designed and adapted for use in flattening or reclaiming printing plates or the like.
- 10 It is also an object of the invention to provide a novel and improved apparatus of this general character comprising two superimposed rolls the peripheries of which being substantially in close contact and between
- 15 which the material to be flattened is adapted to be passed together with means associated with one of the rolls for maintaining the work to be operated upon in proper position with respect to the rolls.
- 20 Another object of the invention is to provide a novel and improved device of this general character especially designed and adapted for use in connection with printing plates or the like connected to provide a
- 25 chain like structure so that the plates to be treated may be successively passed with substantial speed between suitably mounted pressure rolls.
- The invention consists in the details of
- 30 construction and in the combination and arrangement of the several parts of my improved metal straightening apparatus whereby certain important advantages are attained and the device rendered simpler, less
- 35 expensive and otherwise more convenient and advantageous for use, as will be herein-after more fully set forth.
- The novel features of my invention will hereinafter be definitely claimed.
- 40 In order that my invention may be the better understood, I will now proceed to describe the same with reference to the accompanying drawings, wherein:—
- Figure 1 is a view in side elevation illustrating an apparatus constructed in accordance with an embodiment of my invention;
- 45 Figure 2 is a view in front elevation of the apparatus as herein set forth;
- 50 Figure 3 is a fragmentary view in elevation opposite to that illustrated in Figure 1;
- Figure 4 is a fragmentary sectional view illustrating a detail of the invention as herein comprised.
- 55 As disclosed in the accompanying drawings, my improved apparatus comprises a pair of upstanding and suitably disposed supports 1 between which are arranged the rolls R and R' of requisite dimensions, said rolls at similar ends thereof having disposed therearound and formed therewith the intermeshing gears 2 whereby said rolls R and R' may be caused to rotate in unison. The roll R or R' immediately adjacent to the gear has disposed circumferentially therearound a groove 3 whereby the working periphery of each of said rolls is spaced from the gear so that no hindrance or obstruction may be offered by such gear.
- The lower roll R is supported for rotation upon the stud or axle 4 provided with the journals 5 engaged with the supports 1. The roll R' is mounted upon the stud or axle 6 provided with the eccentric journals 7 disposed through the supports 1. By rotation of the stud or axle 6 the roll R' may be adjusted with respect to the roll R as the necessities of practice may require and particularly to regulate the pressure imposed upon the work passing between the rolls R and R'.
- My improved apparatus as herein disclosed is particularly designed for use in connection with that type of printing plates wherein the characters are embossed or similarly formed thereon and which plates are adapted to be connected in chain to provide a flexible strip.
- The periphery of the roll R to the side of the groove 3 opposite from the gear 2 is provided thereacross with the transversely disposed and circumferentially spaced grooves 8 to receive or compensate for the hinged connections 9 between adjacent plates P, the area of the periphery of the roll R between adjacent grooves or channels 8 closely approximating the area of the major or body portion of a plate P.
- As the strip of connected plates P is passed between the rolls R and R' the characters on the plates are flattened out so that said plates can be employed again with new characters produced thereon.
- Extending laterally from one of the supports 1 and preferably adjacent to the bite of the rolls R and R' is an arm 10, said arm being substantially perpendicular to the plane common to the axes of both of the rolls R and R'. Rotatably supported by the outer end portion of the arm 10 is a gear 11 meshing with the gear 2 of the roll R', said gear 11 having a trunnion 12 extending

through the arm 10 and to which trunnion, as herein disclosed, is affixed an operating handle 14. Upon requisite turning of the handle 14, the rolls R and R' may be caused 5 to have requisite rotation for action upon a strip of plates or the like passing therebetween.

While I have herein disclosed my improved machine as of a type for manual 10 operation it is to be understood that if preferred suitable means may be associated with the gear 11 to operate the same by power.

The arm 10 has its inner end portion engaged within a transversely disposed groove 15 produced in the outer face of its associated support 1 and such inner end portion of the arm 10 is provided with a longitudinally disposed slot 16 through which is directed a holding nut 17 in engagement with 20 a support 1. By this means the arm 10 may be longitudinally adjusted as required to maintain the desired engagement of the gear 11 with the gear 2 of the roll R'.

As particularly illustrated in Figure 4 25 the grooves or channels 8 are produced in a removable ring or rim so that the same can be readily replaced when unduly worn or otherwise unfit for use, the same being keyed, as at 18, or otherwise held in applied 30 position. This same arrangement may also be employed in connection with the second or upper roll R' if desired.

One of the supports 1 has pivotally engaged therewith at transversely spaced 35 points 19 the extremities of the downwardly diverging arms 20 constantly urged one toward the other through the means of an interposed retractile member 21 herein disclosed as a coil spring. The outer or free 40 end portion of one of the arms 20 carries a roller 22 the periphery of which being smooth and unobstructed from end to end, said roller bearing down upon and having contact upon the strip after the same has 45 passed between the rolls R and R' and at a predetermined point below the bite of such rolls whereby the functioning of the apparatus is materially facilitated.

The outer or free end portion of the second 50 arm 20 rotatably supports a roller 23 provided at its ends with the outstanding flanges 24, one of said flanges projecting within the groove 3 of the roll R while the opposite flange 24 overlies the outer face of said roll. 55 The strip of material passes under the roller 23 before passing between the rolls R and R' and this roller 23 operates effectively to maintain the strip in desired working position as it travels toward the bite of such rolls R and R'.

From the foregoing description it is thought to be obvious that a metal straightening apparatus constructed in accordance 60 with my invention is particularly well adapted for use by reason of the convenience

and facility with which it may be assembled and operated, and it will also be obvious that my invention is susceptible of some change and modification without departing from the principles and spirit thereof and for this 70 reason I do not wish to be understood as limiting myself to the precise arrangement and formation of the several parts herein shown in carrying out my invention in practice except as hereinafter claimed. 75

I claim:

1. An apparatus for flattening out embossed printing plates pivotally connected to provide a chain like strip comprising two rolls, means for supporting the same in close proximity one to the other whereby the peripheries are substantially in contact, intermeshing gears carried by adjacent ends of the rolls, a rotating medium coacting with one of the rolls, each of said rolls adjacent to the gear being provided therearound with a circumferentially disposed groove whereby the working periphery of the roll is spaced from the gear, the working periphery of one of the rolls being provided with transversely disposed and circumferentially spaced channels to receive the hinged connections between adjacent plates. 90

2. An apparatus for flattening out embossed printing plates pivotally connected 95 to provide a chain like strip comprising two rolls, means for supporting the same in close proximity one to the other whereby the peripheries are substantially in contact, intermeshing gears carried by adjacent ends of the rolls, a rotating medium coacting with one of the rolls, each of said rolls adjacent to the gear being provided therearound with a circumferentially disposed groove whereby the working periphery of the roll is spaced 100 from the gear, the working periphery of one of the rolls being provided with transversely disposed and circumferentially spaced channels to receive the hinged connections between adjacent plates, and rollers 105 coacting with the roll having said channels, said rollers contacting with the plate strip at opposite sides of the bite of the rolls to hold said strip in desired position for passage between the rolls. 110

3. An apparatus for flattening out embossed printing plates pivotally connected to provide a chain like strip comprising two rolls, means for supporting the same in close proximity one to the other whereby the peripheries are substantially in contact, intermeshing gears carried by adjacent ends of the rolls, a rotating medium coacting with one of the rolls, each of said rolls adjacent to the gear being provided therearound with a circumferentially disposed groove whereby the working periphery of the roll is spaced from the gear, the working periphery of one of the rolls being provided with transversely disposed and circumferentially 120 spaced channels to receive the hinged connections between adjacent plates, and rollers 125 coacting with the roll having said channels, said rollers contacting with the plate strip at opposite sides of the bite of the rolls to hold said strip in desired position for passage between the rolls. 130

spaced channels to receive the hinged connections between adjacent plates, and rollers coacting with the roll having said channels, said rollers contacting with the plate strip at opposite sides of the bite of the rolls to hold said strip in desired position for passage between the rolls, one of said rollers having its periphery unobstructed from end to end, the second roller having its ends provided with outstanding flanges, one of said flanges extending within the groove of the roll provided with the channels, the second flange overlying the face of the roll. ¹⁰

In testimony whereof I hereunto affix my signature.

WILLIAM R. SMITH.
